[57] **CLAIM**

The ornamental design for a table or similar article, as
shown and described.

DESCRIPTION

FIG. 1 is a perspective view of a table showing my new
design. The edges of the table are stippled to indicate
that the edges are not transparent;

FIG. 2 is a top view of the table of FIG. 1;

FIG. 3 is a side view of the table of FIG. 1. This view
is the same for all four sides of the table;

FIG. 4 is a bottom view of the table of FIG. 1;

FIG. 5 is a top view of a modified form of the table of
FIG. 1;

FIG. 6 is a side view of the table of FIG. 5. The oppo-
site side of the table is identical to the view shown in
FIG. 6;

FIG. 7 is an end view of the table of FIG. 5. The oppo-
site end of the table is identical to the view shown in
FIG. 7.

While a bottom view of the modified form shown in
FIG. 5 has not been shown, it is to be understood that
such view is identical to the top view of FIG. 5, with
the sole exception of the bottom ends of the four legs
which are identical to the bottom ends of the four legs
shown in FIG. 4. The edges of all four sides of the table
are not transparent. This is shown in FIGS. 6 and 7, and
is true for all forms of the invention, including FIG. 1.
